UNITED STATES PATENT OFFICE.

THOMAS L. HOGAN, OF NEW YORK, N. Y.

SLEEVE-PROTECTOR.

1,278,654.

Specification of Letters Patent. Patented Sept. 10, 1918.

Application filed January 8, 1918. Serial No. 210,848.

To all whom it may concern:

Be it known that I, THOMAS L. HOGAN, citizen of the United States, residing at New York, N. Y., have invented certain new and 5 useful Improvements in Sleeve-Protectors; and I do hereby declare the following to be a full, clear, and exact description of the invention, such as will enable others skilled in the art to which it appertains to make and 10 use the same.

My invention relates to sleeve protectors or cuff protectors, its general objects being to equip a device of this character with simple, cheaply constructed and satisfactory means for maintaining the protector in the shape in which it is adjusted to a particular arm or sleeve. More particularly, my invention aims to provide a tubular sleeve protector constructed entirely out of a cheap 15 material, such as paper, and so equipped that when adjusted to any desired taper, it may readily be latched in this tapering shape without employing auxiliary fastening elements, and may easily be unlatched 20 without damaging any part of the appliance. Heretofore, protectors of this general class (that is to say, sleeve protectors for use of bookkeepers, saleswomen, clerks, and the like) have been constructed in the form of 25 substantially cylindrical tubes and have then been contracted to the desired tapering shape by folding a portion of the tube upon itself, as shown for example in Patent No. 1227052, as issued on May 22, 1917. When thus 30 tapered to fit the particular arm or sleeve over which the protector was used, the folded-over portion was attached to an adjacent part of the protector by some auxiliary means, such as the rubber band illus- 35 trated in my said patent, or the gummed tab shown for the same purpose in my copending application 198020, filed October 23, 1917. Such auxiliary fastening means have not 40 proven entirely satisfactory. In the case of 45 the rubber band, this was apt to snap, and also to catch on any projections over which the protector was moved when in service; while a string or cord when substituted for the same purpose was likewise apt to catch 50 on adjacent objects, and also was likely to become untied. Moreover, such a band or cord if drawn tight would crease the protector, thereby rendering the latter unsightly, and sometimes also causing an unsightly indentation of the sleeve or cuff incased by the adjacent part of the protector. 55

So, also, when the protector was removed, the rubber band or cord was apt to be lost, and where a cord was used, this often could only be untied by enlisting the service of another person. Because of these objections, tubular protectors of the class to which my invention relates have not been used as extensively as they deserve. While a gummed tab when used after the manner of my co-pending application No. 198020 avoids this danger of catching on adjacent objects, it has the other objection of maintaining the protector permanently adjusted, so that the protector if adjusted to a tight fit at the wrist 60 cannot be removed without tearing the gummed tab. In other words, to use the gummed tab fastening for any prolonged period, it has been necessary to adjust the protector to a tube of such size at the wrist 65 that the entire hand could still be withdrawn through it, thereby spoiling the appearance of the protector and somewhat interfering with its effectiveness also.

To overcome these and other objections, 70 my present invention aims to provide a tubular protector made of a material which may readily be partly folded upon itself to afford the desired taper, and equipped with means permanently attached to the protector 75 for engaging the folded-over portion, so as to latch the latter in the position in which it adjusts the tube to the desired effective taper. It also aims to provide the said latching means in such a position that it can readily 80 be operated on one arm of the user by the other hand of the latter, both for latching the protector and for speedily unlatching it when the protector is to be taken off. To accomplish this general purpose, I equip the 85 tubular protector with means for engaging the free tip of the doubled triangular portion which is folded upon the exterior of the tube for effectively tapering the latter, and desirably provide the said tip-receiving means 90 in the form of a socket or pocket entered by the extreme corner portion of the said tip when the said corner portion is turned in between the main portion of the protector and the larger part of the said adjustment-affording triangular fold. The tip-receiving equipment for this purpose may be constructed cheaply and effectively in a number of different ways, some of which are described more fully in the following specification, 95 and illustrated in the accompanying drawings. In these drawings,

Figure 1 is a perspective view of one form of my sleeve protector when in use.

Fig. 2 is a plan view of the same protector in the flattened form in which it is shipped.

Fig. 3 is an enlarged and fragmentary transverse section through a portion of the protector of Fig. 1, showing the operative arrangement of the interlocking parts.

10 Fig. 4 is a fragmentary flattened view of another embodiment, namely one in which the extreme tip of the folded over portion is adapted to be folded into a pocket disposed on the outer surface of the protector.

15 Fig. 5 is a fragmentary flattened view of another type, namely one in which the tip of the adjusting fold is inserted through a slot into the interior of the tubular protector, or into the space between the inner sur-

20 face of the tube and a protective lining.

Fig. 6 is an enlarged fragmentary and transverse section through a protector constructed after the manner of Fig. 5.

25 Generally speaking, I accomplish the purposes of my invention by equipping a portion of a tubular protector with means adapted to be engaged by, or interlocked with, that portion of the tube which is formed into a fold when shaping the tube 30 to the desired taper for fitting the arm of the user. Preferably, I provide such engaging means in a disposition in which the same will engage the extreme tip of the folded-over portion of the tube, and desirably in a disposition in which it will clamp 35 this extreme tip between other portions of the protector, so that any strain tending to enlarge the bore of the protector will squeeze this tip all the more tightly between 40 adjacent parts, while still permitting the tip to be easily withdrawn by a simple manipulation from the exterior of the protector. For example, in the type of Figs. 1 to 3 inclusive, my protector consists of a 45 cylindrical tube of paper or the like, which is flattened as shown in Fig. 2 for convenient storing and shipping and for defining a fold edge in desirable relation to the longer side of the tube, or the side 50 adapted to be under the forearm when the protector is in use. Fastened to this tube 1 at some distance from the longer fold edge is a strap 2, which strap is desirably made of somewhat stronger material than the 55 body of the tube, and which in the type of Fig. 2 is secured to the exterior of the tube only at its ends. In using the protector as thus constructed, the tube is slipped over the arm with the longer fold edge 3 60 downwardly directed, and is then contracted by forming a triangular fold from the portion adjacent to this edge 3, pressing this fold against the body of the tube and turning the extreme forward tip or corner of 65 this fold over between the fold and the body

of the tube, so that this tip can be slid between loose portion of the strap and the part of the tube adjacent thereto. The free tip or corner is desirably inserted between the strap and the tube to such an extent as 70 to draw the remainder of the said fold portion tightly against the body of the tube, whereupon the fold can be pressed tightly against the tube along the upper edge of the strap, thus defining a fold line 4 at the 75 crease of the fold which is hooked over the top of the strap. When the protector has thus been contracted to an arm-fitting or sleeve-fitting shape, it will be obvious from Fig. 3 that any tendency to enlarge the 80 bore of the tapering tube will squeeze or clamp the inserted tip not only between the strap and the main portion of the tube, but also between the latter and the main portion of the fold, so that this clamping action 85 will coöperate with the hooking of the fold over the upper edge of the strap for resisting a withdrawal of the tip by any tendency toward expanding the tube. However, by inserting a pencil or finger under 90 the hook-forming portion of the fold at the exterior of the protector as shown in dotted lines at 5 in Fig. 1, the tip may readily be snapped out of its holding position, thereby permitting the protector to be expanded to 95 its full cylindrical shape, and to be withdrawn over the hand of the user even when the protector had been contracted to a close fit over the wrist. To increase the hold of 100 the tip on a tube of the protector, and particularly to prevent the strap from being loosened from its pasted fastenings along the upper edge of the strap by the inserting of the tip, which inserting may tend to rock the strap downwardly or away from 105 the tube about the lower edge of the strap, I desirably widen the ends of the strap upwardly of the protector, as shown in Figs. 1 and 2. Similar extensions may also be used 110 to advantage when the tip-engaging element is in the form of a pocket (as in Fig. 4), and the hook-engaging edge may be disposed at various angles with respect to the fold edge 3, as shown in the drawings.

115 However, while I have illustrated and described my invention as embodied in a form comprising a paper cylinder and a strap pasted at its ends on the exterior of the latter, I do not wish to be limited to these or other details of the construction and arrangement here disclosed, it being obvious that the same might be modified in many ways without departing from the spirit of my invention. For example, a pocket 7 might be substituted for the said strap as 120 shown in Fig. 4; or, the inwardly folded free tip of the main fold might be inserted through a slot 8 in the main portion of the tube so as to extend into the interior 125 of this tube, as shown in Fig. 5. With the 130

last named construction, I preferably equip the tubular protector upon its interior with a guard strip or backing 9 which will bear against the sleeve of the wearer to prevent 5 the inserted tip of the protector from catching on the material of this sleeve.

With any of the embodiments thus described, it will be evident from the drawings that the protector of my invention can 10 readily be adjusted to fit arms or sleeves varying considerably in size, and that the combined clamping and hooking action will securely maintain the protector in this adjusted position when in normal service. However, the latching tip or corner can readily 15 be unlatched as above described, thus permitting the protector to be flattened out again when not in service. Then, the previously defined fold lines will expedite a 20 repetition of the same adjustment for the protector, thus making the same unusually convenient and serviceable for continued use until soiled. Moreover, the cheapness of the needed material, and the simplicity of construction should make my protector so low 25 in cost as to permit of its widespread introduction. To adapt the protector more adequately to the shape of the arm, I desirably shorten the tube at its upper edge, or the 30 one opposite the said fold edge 3, and desirably curve both ends of the tube, somewhat after the manner illustrated in the drawings. However, I do not wish to be limited to such a shape, as it will be obvious 35 that the taper-maintaining feature of my invention would operate equally well regardless of the shape of the ends of the tube.

I claim as my invention:

1. A sleeve protector comprising a substantially unbroken tube of flexible material, 40 and means fast upon the tube for engaging the tip of a triangular fold formed from said tube.

2. A sleeve protector comprising a substantially unbroken tube of flexible ma- 45

terial, and means fast upon the tube for engaging the tip of a triangular fold formed from said tube when the said tip is folded between the body of the tube and an adjacent part of the tube. 50

3. A sleeve protector comprising a tube of flexible material and an auxiliary member fastened to the tube at a pair of spaced points, the said member having an intermediary portion spaced from the tube to afford a socket for receiving the inwardly folded tip of a triangular fold formed from the tube. 55

4. A tapering sleeve protector comprising a tube of sheet material and anchoring means carried thereby, a portion of the said tube being formed into a substantially triangular double-thickness fold and the free tip of the said fold being doubled back upon the said fold to afford a hook engaging the said anchoring means. 60

5. A sleeve protector comprising a substantially unbroken tube of flexible material, and means fast upon the tube for clamping socketing the doubled tip of a triangular fold formed from a portion of the said tube. 70

6. A sleeve protector comprising a tube of flexible material having a portion thereof formed into a tapering fold bearing against the outer surface of the said tube for effectively tapering the tube, and means carried by the tube and over which the free corner of the said tapering fold may be hooked to hold the latter in its tube-tapering position, the said means being so disposed as to permit the insertion of the said corner between the same and an adjacent portion of the protector, thereby causing any expanding tendency of the tapering tube to clamp the said corner between the last named two parts of the protector. 80

Signed at Chicago, December 31st, 1917.

THOMAS L. HOGAN.
